UNITED STATES PATENT OFFICE

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY

SHOE-RAND-CEMENTING MACHINE

Application filed June 30, 1927. Serial No. 202,589.

This invention relates to rand treating machines and is illustrated as embodied in a machine for cementing either horseshoe-shaped or straight rands.

5 The beveled strips of material which are used in the manufacture of shoe rands vary greatly as to quality so that some are comparatively firm and semi-rigid strips, while others are of very flimsy material and have 10 soft irregular edges, especially at the thin edge. Frequently, too, the strips become distorted between the time that they are cut and the time when they are taken out for use so that, in transverse section, instead of being 15 in the form of a right-angled triangle, they are curled transversely. Such strips, if dry and stiff, are somewhat difficult to handle, especially when presented for treatment, as to a machine for applying cement to one 20 surface of a rand strip.

Accordingly, one object of the invention is to provide an improved machine for treating beveled rand strips wherein the handling of the strips will be greatly facilitated regardless of their characteristics and particular shapes.

To this end, the illustrated machine is provided with a cement-applying roll having a concave periphery so that even though the 30 strip may have curled transversely it will be possible to apply cement evenly to the whole width of one surface of the curled strip. Co-operating with this applying roll is a presser roll having a periphery convex 35 in transverse cross-section, one end face of which is larger in diameter than the other end face. This larger portion of the illustrated roll is arranged to contact with the thinner edge of the beveled strip thereby to 40 press it firmly into contact with the face of the applying roll. Divergent guides are preferably provided to facilitate the introduction of the ends of rands, especially the flimsy ones, into the machine.

45 Some rands, known to the trade as "turned" rands, are formed into approximately horseshoe-shaped strips of material and in the presentation of such strips to a treating machine, it has been necessary for 50 the operator to hold on to the strips and turn

them so as to present the whole length, including the curved closed ends of the horseshoe-shaped strips and the two sides, to the action of the machine.

Accordingly, another object of the invention is to provide a machine by the use of which treatment of horseshoe-shaped strips of material will be facilitated. To this end, the illustrated machine is organized to guide such a strip automatically through the machine after one end thereof has been taken up by the feeding mechanism.

In accordance with another feature of the invention, a machine having feeding means urging the strips forward in a straight path, 65 is provided with a guide which is disposed laterally of the path of movement of the strips and which is arranged to contact with the inner rim of each horseshoe-shaped strip, thereby to turn it around so that the whole 70 length of each strip will be fed automatically through the machine.

In the drawings,

Fig. 1 is a perspective view of a rand cementing machine embodying the invention;

75 Figs. 2 and 3 are plan views of the applying roll of the machine and the guides, showing the action of the machine in guiding a horseshoe-shaped strip of material automatically to the applying roll:

80 Fig. 4 is a side elevation, with parts broken away and in section, of the machine shown in Fig. 1; and

85 Fig. 5 is an enlarged section through the co-acting rolls and an interposed rand strip.

The operating parts of the illustrated rand cementing machine are mounted upon a base 10 at one side of which there is provided a drive pulley 12 which is connected through gears 14 and 16 to a presser roll 18 and a treating roll 20 mounted on shafts 15 and 17 respectively. This treating roll 20 is a cement-applying roll and is journaled in a cement receptacle 22 having a supply reservoir 24, the receptacle being pivotally mounted upon a pin 26 and urged upward to grip the work by means of a spring 28 within the base 10. The tension of this spring may be adjusted by a hand nut 30 and the upward movement of the roll is limited by a stop screw 32. The 100

amount of cement taken up by the roll may be controlled in any suitable manner, the illustrated machine being provided with an adjustable scraper 34 for this purpose.

In order to adapt the machine especially for the treatment of beveled rand strips which may have become curled transversely so that the strips 40 have assumed a form such as that shown in section in Fig. 5, the applying roll 20 is made with its periphery concave in transverse cross-section as indicated at 42 so that even though the strip may be hard and semi-rigid, it will be possible to apply cement evenly across the whole width of the strip. This result is still further facilitated by the construction of the presser roll 18, which, as may be seen from Fig. 3, is provided with a periphery which is convex in transverse cross-section and is made larger at its outer end 44 than it is at its inner end 46. The larger end 44 is made to coact with the thin edge of each rand strip 40 while the smaller inner end coacts with the thicker edge to hold the whole width of the strip in contact with the treating roll. It is not necessary that the transverse cross-section of this presser roll shall exactly correspond to the transverse cross-section of the upper side of any particular thickness of the beveled strip as it rests on the treating roll as the presser roll must coact with various sizes of strips and the natural resistance to deformation of the strip will help to hold down the strip at the edges when the presser roll 18 acts along the middle.

The combined action of the rolls 18 and 20 upon the strip 40 is to urge it forward in a straight path and the guidance of strips presented to the machine is facilitated by the use of a flat-faced guide member 50 having a supporting stud 52 by means of which it is adjustably supported upon a lug 54 forming part of the receptacle 22. The stud 52 is held on the lug 54 by means of a clamping screw 56.

The presentation of beveled rand strips to the machine is still further facilitated by the provision of guide flanges 60 and 62 extending outwardly from the face of the guide member 50 at its forward portion. As may be seen by an inspection of the drawings, these guide flanges 60 and 62 are so related to one another that they diverge outwardly toward the front of the machine, thus forming an open mouth to which it is easy to present the advancing end of each strip, thereby to locate the strip exactly between the bite of the rolls. The guide flanges 60 and 62 are also disposed in divergent directions transversely of the path of feeding movement so that they converge near the outer edge of the rolls and form a triangular-shaped opening corresponding approximately to the cross-sectional shape of the beveled rand strips. These guide flanges are found especially de-

sirable when the machine is to be used for rand strips which are soft and flimsy and aid the operator in feeding the strips correctly to the machine so that they will not be diverted from between the rolls and passed diagonally out of the machine without receiving proper treatment.

When the machine is to be used for cementing horseshoe-shaped "turned" rand strips 70, the approximate shape of which is illustrated in Figs. 2 and 3, then a guide 72 is provided which is disposed laterally of the path of movement of the strips and forwardly of the axis of the rolls for engagement with the inner rim 74 of each of the horseshoe-shaped strips of material. This guide 72 is pivotally mounted in a bracket 76 and its position transversely of the path of movement of the strips may be determined by means of a hand screw 78 acting in opposition to a spring 80 inserted between the bracket 76 and the guide 72.

The action of the guide 72 is to contact with and exert a drag upon the inner rim 74 of each of the horseshoe-shaped strips 70, thereby automatically to turn it as it is pulled forward by the feeding means so that after one of the open ends of the horseshoe-shaped strips has been presented to the machine and its feeding movement started, the machine will treat first one of the straight sides, then the closed curved end of the strip, and then the other straight side without interference upon the part of the operator, this action being illustrated in Figs. 2 and 3. It will be understood that the guiding action of the guide 72 is effective either with or without the guide 50 and the flanges 60 and 62, although in the preferred form of the invention, these guide flanges and the flat-faced guide member 50 are combined with the guide 72 and all work together to make a machine which is semi-automatic in its operation and which allows the treatment of a large number of horseshoe-shaped strips of material in a short time without reducing the quality of the work produced.

It will be understood also that, in various respects, the invention is not limited to embodiment in the particular type of machine shown and described or to the performance of the particular operations referred to. The scope of the invention should be determined by the accompanying claims, giving the broadest construction to the terms of the claims which is permitted by the prior art.

Having thus described my invention, what I claim as new and desire to secure by Letters Patent of the United States is:

1. In a machine for treating beveled rand strips, a treating roll having a concave periphery and a presser roll having a convex periphery in transverse cross-section cooperating with said treating roll and arranged to press against the other side of a rand strip being treated by the treating roll.

2. In a machine for cementing beveled rand strips, a cement-applying roll having a grooved periphery the transverse cross section of which approximately fits a curled rand strip, and a presser-roll having a periphery the transverse cross-section of which is convex and non-complementary to said applying roll cooperating with the other side of said strip to hold one face of the beveled strip in contact with the applying roll.

3. In a machine for cementing beveled rand strips, an applying roll, and a presser roll having a convex periphery in transverse cross-section, one end portion of which is of larger diameter than the other end portion.

4. In a machine for cementing beveled rand strips, an applying roll having a concave periphery in transverse cross-section, and a presser roll having a convex periphery in transverse cross-section, one end portion of which is of larger diameter than the other end portion.

5. In a machine for cementing beveled rand strips, an applying roll, a presser roll having a convex periphery in transverse cross-section so that one end portion of the roll is of larger diameter than the other end portion, the larger portion of said presser roll being arranged to contact with the thinner edge of a beveled strip thereby to press it firmly into contact with the face of the applying roll.

6. In a machine for treating beveled rand strips, treating means, a guide-plate disposed laterally of the path of movement of a strip presented to said treating means to form an edge gage for said strip and rigid guides on said plate extending outwardly above and below the path of movement of the strip and angularly disposed with respect to one another along the path of movement so as to form an outwardly flared mouth, said rigid guides being also directed toward each other as they recede from said plate to provide a guide opening which converges transversely with respect to said path of movement.

7. In a machine for cementing beveled rand strips, a cement applying device constructed and arranged to feed the strips, a guide-plate disposed laterally of said cement-applying device and guide flanges upon said guide diverging toward the opening of said guides and laterally toward said guide plate.

8. In a machine for treating horseshoe-shaped strips of material, treating means, feeding means urging the strips forward in a straight path, and means contacting with a curved peripheral edge of the strips constructed and arranged automatically to guide said horseshoe-shaped strips to the treating means after one end of said strips has been taken up by the feeding means.

9. In a machine for treating horseshoe-shaped strips of material, treating means, feeding means urging the strips forward in

a straight path, and strip deflecting means for automatically turning said horseshoe-shaped strips to present all portions of the length of said strips to said treating means.

10. In a machine for treating horseshoe-shaped strips of material, treating means, feeding means urging the strips forward in a straight path, and fixed strip engaging means arranged automatically to reverse said horseshoe-shaped strips during their treatment so that the whole length of each strip is presented to the treating means.

11. In a machine for treating horseshoe-shaped strips of material, treating means, feeding means urging the strips forward in a straight path, and guide means contacting with one periphery of said horseshoe-shaped strips arranged automatically to guide said strips to present the whole length of the strips to the treating means.

12. In a machine for treating horseshoe-shaped strips of material, treating means, feeding means urging the strips forward in a straight path and a guide disposed laterally of the path of movement of the strips constructed and arranged to contact with the inner rim of each horseshoe-shaped strip, thereby automatically to turn it about so that the other side of the horseshoe is fed along by said feeding means for treatment without interference on the part of the operator.

13. In a machine for treating horseshoe-shaped strips of material, feeding means urging the strips forward in a straight path and a guide disposed laterally of the path of movement of the strips, in advance of the point of contact of the feeding means with the strip, constructed and arranged to contact with the inner rim of each horseshoe-shaped strip thereby automatically to turn it about so that the other side of the horseshoe is fed along by said feeding means for treatment without interference on the part of the operator.

14. In a machine for treating horseshoe-shaped strips of material, a driven treating roll, means for holding a strip of material in contact with said roll to cause it to be dragged forward in a straight path by said roll, and a guide disposed laterally of the path of movement of the strip for contact with the inner rim of the horseshoe-shaped strip, whereby the curved portion of the strip engages the guide as the strip is dragged along by said roll and the strip is automatically turned so that its other end is treated by the roll.

15. In a machine for treating horseshoe-shaped strips of material, a rotary member for engagement with the surface of a strip, means for holding said strip in contact with said rotary member causing the strip to be fed thereby in a straight path, and guides at either side of the path of movement for the

strips and disposed laterally of the plane of rotation of said member, one of said guides being arranged to contact with the inner rim of each horseshoe-shaped strip to exert a drag thereon tending to rotate the strip at the closed end thereof automatically to bring the other side of the horseshoe-shaped strip toward the other guide into said path of movement.

10 16. In a machine for treating horseshoe-shaped strips of material, feeding means urging the strips forward in a straight path, and guides disposed laterally of the path of movement of the strips, one of said guides 15 having a flat face for guiding the outer rim of each strip and the other guide constructed and arranged to contact with the inner rim of each strip whereby the horseshoe-shaped strips of material may be fed automatically 20 through the machine after one of the ends of each horseshoe-shaped strip has been presented to the machine.

17. In a machine for treating horseshoe-shaped strips of material, a treating roll, 25 means for holding a strip in contact with said treating roll, an elongated flat-faced guide member alongside said treating roll, and a guide adjacent to the other side of the treating roll and disposed forwardly of the 30 axis of the treating roll whereby said horseshoe-shaped strip, after one of the open ends thereof has been presented to the treating roll, will be automatically turned around the guide to present the whole length of the 35 strip for treatment by said roll.

18. In a machine for cementing horseshoe-shaped rands, a receptacle, a cement-applying roll dipping in said receptacle, a presser roll above said cement-applying roll, an elongated straight guide adjacent to one side of the applying roll, and a post guide adjacent to the other side of the applying roll, constructed and arranged to exert a drag on the inner rim of the horseshoe-shaped rand to 45 turn it toward the flat-faced guide so that it will be automatically cemented by the machine after one of the open ends of the rand has been presented to said rolls.

19. In a machine for cementing horseshoe-shaped beveled rand strips, an applying roll having a concave periphery, a cooperating presser roll having a periphery convex in transverse cross-section with one end portion larger than the other end portion and 55 guides associated with the lateral faces of said applying roll, one of said guides being provided with an elongated, flat face to contact with the outer rim of the horseshoe-shaped strip, the other guide having a single bearing point for engagement with the inner rim of the horseshoe-shaped strip and being constructed and arranged to exert a drag on said strip at the closed end of the horseshoe to 60 turn the horseshoe-shaped strip around so 65

that the whole length thereof is automatically treated by the machine.

In testimony whereof I have signed my name to this specification.

JOHN W. COSGROVE.
